Primary Examiner — Omeed Agilee(74) *Attorney, Agent, or Firm* — Ballard Spahr LLP(57) **CLAIM**

The ornamental design for an electrode array as shown and described.

DESCRIPTION

FIG. 1 is perspective view of an electrode array showing our new design;

FIG. 2 is a top plan view of the electrode array of FIG. 1; FIG. 3 is a front elevational view of the electrode array of FIG. 1;

FIG. 4 is a rear elevational view of the electrode array of FIG. 1;

FIG. 5 is a left side elevational view of the electrode array of FIG. 1; and,

FIG. 6 is a right side elevational view of the electrode array of FIG. 1.

The broken lines and unshaded areas between and bounded by the broken lines and solid lines, depict portions of the electrode array that form no part of the claimed design.
